NATHAN F. MATHEWSON, OF BARRINGTON, RHODE ISLAND.

Letters Patent No. 85,946, dated January 19, 1869.

IMPROVED CARRIAGE-CURTAIN BUTTON.

The Schedule referred to in these Letters Patent and making part of the same.

To all whom it may concern:

Be it known that I, NATHAN F. MATHEWSON, of Barrington, in the county of Bristol, and State of Rhode Island, have invented a new and improved "Carriage-Button;" and I do hereby declare that the following specification, taken in connection with the drawings making a part of the same, is a full, clear, and exact description thereof.

Figure 1 shows the simple form of carriage-button now in use.

Figure 2 is a view of my improved button.

Figures 3 and 4 are views of the same.

It is well understood that the enamelled cloth with which carriages are usually covered, when subjected to the rays of the sun, and to the atmosphere, for any length of time, shrinks and becomes dry and hard, so that the buttoning and unbuttoning of the same is not only a matter of great difficulty and perplexity, but frequently results in the rending of the cloth, thereby detracting much from the appearance of the carriage, as well as rendering a new covering, or the repairing of the old one, often and absolutely necessary.

To overcome these defects is the object of my invention, which I will now proceed to describe.

I make use of a shank, A, constructed with a pin or

screw and shoulder at one end, (as in the ordinary carriage-button represented in fig. 1,) and having a button, B, hinged to the other end, as shown in fig. 2.

Commencing with the parts in the position shown in fig. 2, when it is desired to button or unbutton the cloth, the button B may be turned upon its hinge, the tongue being rounded at one corner, so as to occupy the position shown in figs. 3 and 4.

The shank A being cut out at the point C, receives the end of the button, so that both shank and button are of no greater thickness than an ordinary shank. While in this position, the cloth may be slipped over the button with ease, and without tearing or enlarging the button-hole, and the button B turned back to its proper position, shown in fig. 2.

What I claim as my invention, and desire to secure by Letters Patent, is—

The combination of the shank A and button B, the whole constructed and arranged substantially as and for the purposes specified.

NATHAN F. MATHEWSON.
